UNITED STATES PATENT OFFICE.

JOSEPH B. HALL, OF CHICAGO, ILLINOIS, ASSIGNOR TO MCGUIRE MANUFACTURING COMPANY, OF CHICAGO, ILLINOIS, A CORPORATION OF ILLINOIS.

STREET-SPRINKLER.

No. 838,107.

Specification of Letters Patent.

Patented Dec. 11, 1906.

Application filed August 18, 1903. Serial No. 169,952.

To all whom it may concern:

Be it known that I, JOSEPH B. HALL, a citizen of the United States, residing at Chicago, in the county of Cook and State of Illinois, have invented certain new and useful Improvements in Street-Sprinklers, of which the following is a specification, reference being had to the accompanying drawings.

My invention relates to street-sprinklers, and has particularly to do with the construction and operation of sprinkler-heads designed for use on sprinkling carts or cars.

The objects of my invention are to provide a new and improved construction of sprinkler-head containing in itself all the parts necessary to fulfil every requirement—*i. e.*, to start and stop the flow of water, to discharge the water at either side of the sprinkler-head, and to regulate the quantity discharged at either side; also, to provide an improved construction whereby every operation of adjustment and control of the sprinkler-head may be effected from the platform without inconvenience to the operator. I accomplish these objects as hereinafter described and as illustrated in the drawings.

What I regard as new is set forth in the claims.

In the accompanying drawings, Figure 1 is a partial side elevation of the platform of a car or cart, showing my improved sprinkler-head in position, together with the operating mechanism therefor. Fig. 2 is an end view of the parts shown in Fig. 1. Fig. 3 is a longitudinal vertical section of the sprinkler-head. Fig. 4 is an end view of the sprinkler-head. Fig. 5 is an end view of the sprinkler-head, the removable member thereof being removed, certain parts being in section; and Fig. 6 is a side elevation of said removable member or head.

Referring to the drawings, 10 indicates the platform of the car, and 11 the sprinkler-head, which is secured by an upwardly-projecting lug 12 to one of the sills 13 of the car. While this construction is preferred, the sprinkler-head may, however, be secured to the car or cart in any other suitable manner.

14 indicates the main supply-pipe, through which the water is supplied to the sprinkler-head.

The construction of the sprinkler-head is best shown in Fig. 3, from an inspection of

which it will be seen that the pipe 14 communicates with a chamber 15, which may be termed the "main-valve" chamber. The casing or shell of the sprinkler-head is made up of three members, two of which are rigidly secured together, the third member being movable toward and from the intermediate member for the purpose of controlling the area of the discharge passages or slots, as hereinafter described.

16 17 indicate the stationary members, and 18 the movable member or head. As shown in Fig. 3, the member 17 is intermediately arranged and is firmly secured to the end member 16 by bolts 19, which pass through peripheral flanges 20 21, carried by the members 16 17, respectively. A packing 22 is provided between said flanges to prevent leakage. The intermediate member 17 is also provided with an internally-projecting flange 23, which forms a valve-seat for the main valve of the sprinkler-head, as will be hereinafter described.

The construction of the movable member or head 18 is best shown in Figs. 3 and 6. From an inspection of the latter figure it will be seen that the inner edge of the head 18 is partly cut down, providing a projecting strip 24. Said strip extends through an arc of about one hundred degrees and fits into a corresponding recess in the outer edge of the intermediate member 17, as indicated in Fig. 3. The outer edge 25 of the projecting portion 24 of the head 18, together with the opposing edge of the intermediate member 17, forms one of the slots through which water is discharged from the sprinkler-head, while the edge 26 of the main portion of the head 18, together with the opposing edge portion of the intermediate member 17, forms another slot for the discharge of water. Obviously by adjusting the head 18 toward and from the intermediate member 17 the width of said slots may be adjusted at pleasure. The head 18 is adjustably supported by means of a sleeve 27, which is formed integral with the head 18 and is concentric therewith, said sleeve being mounted upon a tubular support 28, carried by a bracket 29, which is secured to the outer surface of the flange 21 by means of the bolts 19, as shown in Fig. 3. Said bracket extends over the members 17 18 to a point a sufficient distance

beyond the outer end of the sleeve 27 to permit said sleeve to be adjusted freely thereupon. By this construction the head 18 may readily be moved toward and from the intermediate member 17, and the area of the discharge-slots thereby regulated. For the purpose of adjusting the head 18 a lever 30 is provided, which is pivoted at 31 upon the bracket 29 and is provided with a fork 32, which fits in an annular recess 33 in the sleeve 27, as shown in Fig. 3. The upper end of said lever 30 is provided with an eye 34, which fits upon a reduced portion of a screw-shaft 35, mounted in a threaded support 36, which is secured in any suitable way to one of the sills 13, so that by rotating the shaft 35 it may be slowly moved up and down, correspondingly rocking the lever 30 and adjusting the head 18. To prevent leakage between the sleeve 27 and the support 28, an annular packing-strip 37 is provided, which is held in place by a ring 39, secured by screws 40 in the inner end of the sleeve 27 adjacent to the support 28, as shown in Fig. 3.

41 indicates a regulating-valve by which the operative length of the slot at one side of the sprinkler-head may be adjusted. 42 indicates a similar valve for the other slot. As shown in Figs. 3 and 5, said valves 41 and 42 are segmental in form, being curved to fit the interior surface of the sprinkler-head, so as to lie closely over their respective slots. Strips 43, of leather or other suitable material, are provided between the valves 41 42 and the interior surface of the sprinkler-head, so as to insure water-tight contact. The valve 42 is carried at the inner end of a tubular shaft 44, fitting closely in the support 28, through which it extends, as shown in Fig. 3. The shaft 44 is provided near its inner end with a peripheral flange 45, which bears against the inner edge of the support 28, thereby preventing said shaft 44 from being forced out of the sprinkler-head. The valve 41 is carried at the inner end of a tubular shaft 46, which fits closely inside of the shaft 44, through which it extends, as shown in Fig. 3. The shaft 46 is provided near its inner end with a peripheral flange 47, which bears against the inner end of the shaft 44 and serves the same purpose as the flange 45.

48 indicates an arm fixedly secured upon the outer end of the shaft 44 for rocking said shaft to adjust the valve 42. 49 indicates a similar arm secured upon the outer end of the shaft 46 for rocking said shaft to adjust the valve 41. By rocking either of said arms the corresponding valve may be adjusted to vary the operative length of the corresponding slot, thereby controlling the length of the stream discharged at either side of the sprinkler-head. As best shown in Fig. 5, the valves 41 42 are connected with their respective shafts by pins 50, the outer ends of which fit loosely in

bosses 51 in the inner surfaces of said valves, and in order to hold the valves closely in contact with the inner surface of the sprinkler-head springs 52 are provided, which fit upon said pins, the outer ends of said springs bearing against the bosses 51, while their inner ends bear against collars 53, carried by the pins, as shown in Fig. 5. The valves are thus held closely, though yieldingly, in contact with the inner surface of the sprinkler-head.

54 indicates an operating-bar which is connected to the arm 49 and extends up to the platform of the car, where it is provided with a handle 55, by which it may be conveniently operated. By adjusting the bar 54 the arm 49 may be rocked to adjust the regulating-valve 41.

56 57 indicate pins carried by the bar 54 to limit its movement in either direction, one 85 of said pins being above and the other below the platform 10, as shown in Fig. 2.

58 indicates a lever mounted on a pivot 59 and connected with the arm 48 for adjusting the regulating-valve 42. As best 90 shown in Fig. 1, the lower end of the lever 58 extends through a slot in a block 60, mounted on trunnions between the outer ends of the arm 48, which is bifurcated, as shown in Fig. 1. Consequently by rocking the lever 58 in either direction the valve 42 may be correspondingly adjusted.

61 indicates the stem of the main valve. As shown in Fig. 3, the valve-stem 61 is fitted in the tubular shaft 46, extending through said shaft from end to end. At its inner end the stem 61 carries the main valve 62 and a disk 63, of leather, which is placed between said valve and the seat 23. Nuts 64 65 are provided on the stem 61 for adjusting the valve 62 and disk 63, as may be desired.

The outer end of the stem 61 is provided with a nut 66 to limit its inward movement, as shown in Figs. 1 and 3. 67 indicates a treadle for operating the main valve 62. As 105 shown in Fig. 1, said treadle projects through the platform 10, its lower end being connected by a connecting-link 68 with a rock-shaft 69, pivoted at its ends between hangers

70 71, secured to one of the sills 13, as shown 110 in Fig. 2. The rock-shaft 69 is provided with an upwardly-projecting lug 70', with which the outer end of the valve-stem 61 is connected, as best shown in Figs. 1 and 2. By this construction when the treadle 67 is 115 depressed the shaft 69 is rocked to throw the lug 70 inward toward the sprinkler-head, thereby opening the main valve. Upward movement of the treadle closes the main valve.

In order to close the main valve 125 automatically, a spring 72 is provided upon the stem of the treadle 67, as best shown in Fig. 2 and in dotted lines in Fig. 1. As shown in Fig. 2, the lower end of the spring 130 is supported by a hanger 73, secured to the

platform 10, its upper end bearing against a collar 74, carried by the treadle 67 and held in position by a pin 75. The spring 72 is a compression-spring and acts to raise the 5 treadle 67 when depressed, and consequently operates to close the main valve 62.

In order to hold the main valve open when desired, the treadle 67 is provided with a notch 76, adapted to receive a tooth 77, carried by a spring-plate 78, when the treadle 67 is depressed sufficiently. The treadle may be released and the main valve closed by simply pressing it away from the plate 78 far enough to disengage the tooth 77. Instead of using this form of locking device 15 any other equivalent means may be employed to lock the main valve in its open position.

From the foregoing description it will be 20 seen that not only may the volume of water discharged at either side be independently regulated, but also that the discharge may be entirely cut off either by operating both regulating-valves or by closing the main 25 valve. Moreover, the pressure of the water may be controlled by adjusting the main valve and the discharge may be regulated by adjusting the width of the slots. Each of 30 the regulating-valves swings through an arc of about ninety degrees, but they may be as much longer as may be necessary to overlie their respective slots throughout the entire length thereof. For example, the valve 42 extends through an arc of about two hundred and seventy degrees, although only 35 about ninety degrees of its slot is operative, the greater part of the valve serving to close permanently that part of its slot which is not intended to be operative.

I wish it to be understood generally that 40 my invention is not restricted to the specific details of the construction described, except in so far as they are particularly claimed, as my invention includes the use of mechanical 45 equivalents for the different elements of the combinations claimed.

What I claim as my invention, and desire to secure by Letters Patent, is—

1. In a sprinkling apparatus, the combination 50 of a sprinkler-head having a stationary member and a movable member arranged with their edges abutting to form a plurality of slots for the discharge of water, and means for adjusting said movable member for varying the width of said slots, substantially as described.

2. In a sprinkling apparatus, the combination 60 of a sprinkler-head having members arranged with their edges in juxtaposition to form a plurality of slots for the discharge of water, means for adjusting the relative position of said members for varying the width of said slots, and means for varying the length of said slots, substantially as described.

65 3. In a sprinkling apparatus, the combina-

tion of a sprinkler-head having members arranged with their edges in juxtaposition to form a plurality of slots for the discharge of water, means for adjusting the relative position of said members for varying the width of 70 said slots, and independent means for varying the length of said slots, substantially as described.

4. In a sprinkling apparatus, the combination 75 of a sprinkler-head having members arranged with their edges in juxtaposition to form a discharge-slot, means for adjusting the relative position of said members for varying the width of said slot, means for varying the length of said slot, and an independent valve for controlling the admission of water to said slot.

5. In a sprinkling apparatus, the combination 80 of a sprinkler-head having members arranged with their edges in juxtaposition to form a plurality of slots for the discharge of water, means for adjusting the relative position of said members for varying the width of said slots, means for varying the length of said slots, and an independent valve for controlling the admission of water to said slots, 85 substantially as described.

6. In a sprinkling apparatus, the combination 90 of a sprinkler-head, members arranged with their edges abutting to form a slot for the discharge of water therefrom, one of said members being movable relatively to the other, and means for adjusting the operative length of said slot, substantially as described.

100 7. In a sprinkling apparatus, the combination 95 of a sprinkler-head, members arranged with their edges in juxtaposition to form a slot for the discharge of water therefrom, means for adjusting the operative length of said slot, a main valve for controlling the admission of water to said slot, and independent means for operating said main valve, substantially as described.

105 8. A sprinkler-head having a plurality of members arranged with their edges abutting to form a discharge-slot, means within the sprinkler-head for adjusting the length of said slot, one of said members being movable relatively to the other, and means for adjusting said members to vary the width of said slot, substantially as described.

110 9. A sprinkler-head, having a plurality of members having their edges abutting and arranged to form a plurality of substantially 115 parallel discharge-slots, one of said members being movable relatively to the other to vary the width of said slots.

120 10. A sprinkler-head, having a plurality of members arranged with their edges abutting to form a discharge-slot, means for adjusting one of said members toward and from the other to vary the width of said slot, and a rotary internal valve for varying the length of said slot, substantially as described.

11. A sprinkler-head, having a plurality of members arranged with their edges abutting to form a discharge-slot, means for adjusting one of said members toward and from the other to vary the width of said slot, a rotary internal valve for varying the length of said slot, and external means for operating said valve, substantially as described.
12. A sprinkler-head, comprising a stationary member, a movable member, the adjacent edges of said members being arranged to coact to form a discharge-slot, one of said members having a projecting portion adapted to fit in a corresponding indentation in the other member, and means for varying the length of said slot, substantially as described.
13. A sprinkler-head, comprising a stationary member, a movable member, the adjacent edges of said members being adapted to coact to form a discharge-slot, one of said members having a projecting portion adapted to fit in a corresponding indentation in the other member, and an internal valve for said slot, substantially as described.
14. A sprinkler-head, having a plurality of members arranged with their edges in juxtaposition to form a discharge-slot, means for adjusting one of said members toward and from the other to vary the width of said slot, and an internal valve for regulating the discharge of water from said slot, substantially as described.
15. A sprinkler-head, having a stationary member, a movable member, one of said members having a projecting portion in its inner edge adapted to fit in an indentation in the opposite edge of the other member thereby forming a plurality of discharge-slots, and internal valve mechanism for regulating the discharge of water from said slots, substantially as described.
16. A sprinkler-head, having a stationary member, a movable member, one of said members having a projecting portion in its inner edge adapted to fit in an indentation in the opposite edge of the other member thereby forming a plurality of discharge-slots, internal valve mechanism for regulating the discharge of water from said slots, and means for adjusting said movable member toward and from said stationary member, substantially as described.
17. A sprinkler-head, having a plurality of members arranged with their edges in juxtaposition to form a plurality of discharge-slots, a plurality of rocking valves in said head adapted to regulate the operative length of said slots respectively, and means for rocking said valves, substantially as described.
18. A sprinkler-head, having a plurality of members arranged with their edges in juxtaposition to form a plurality of discharge-slots, a plurality of rocking valves in said head adapted to regulate the operative length of said slots, respectively, and concentric sleeves connected with said valves for rocking the same, substantially as described.
19. A sprinkler-head, having a discharge-slot, a rocking valve within said head, a tubular stem for said valve, an independently-operating main valve controlling the passage of water through said sprinkler-head, a stem for said main valve extending through said tubular stem, and means for reciprocating said main valve stem in said tubular stem, substantially as described.
20. A sprinkler-head, comprising stationary members secured together, a valve controlling the flow of water from within one of said stationary members to the other, a movable member coacting with the latter member to form one or more discharge-slots, means for moving said movable member to vary the width of said slots, and independent means for operating said valve, substantially as described.
21. A sprinkler-head, comprising a plurality of members having their edges arranged in juxtaposition to form one or more discharge-slots, one of said members being movable toward and from the other to vary the width of said slot or slots, a valve-chamber adjacent to the chamber formed by said members and having a passage for the admission of water thereto, a valve for controlling said passage, and a longitudinally-movable valve-stem for operating said valve, substantially as described.
22. A sprinkler-head, comprising a plurality of members having their edges arranged in juxtaposition to form one or more discharge-slots, one of said members being movable toward and from the other to vary the width of said slot or slots, a valve-chamber adjacent to the chamber formed by said members and having a passage for the admission of water thereto, a valve for controlling said passage, a longitudinally-movable valve-stem for operating said valve, one or more rocking valves for controlling the length of said slot or slots, and means for rocking said rocking valves, substantially as described.
23. A sprinkler-head, comprising a stationary portion, a movable head therefor, a tubular support upon which said head is carried, a rocking regulating-valve within said sprinkler-head, a tubular stem for said regulating-valve extending through said support, a main valve in said sprinkler-head, and a reciprocating stem therefor extending through said support, substantially as described.
24. A sprinkler-head, comprising a stationary portion, a movable head therefor, a tubular support upon which said head is carried, a rocking regulating-valve within said sprinkler-head, a tubular stem for said regulating-valve extending through said support, a main valve in said sprinkler-head, a reciprocating stem therefor extending through said support, in combination with a platform,

and means for operating said valves from said platform, substantially as described.

25. A sprinkler-head, comprising a stationary portion, a movable head therefor, a tubular support upon which said head is carried, a rocking regulating-valve within said sprinkler-head, a tubular stem for said regulating-valve extending through said support, a main valve in said sprinkler-head, a reciprocating stem therefor extending through

said support, in combination with a platform, means for operating said valves from said platform, and means for adjusting said head from said platform, substantially as described.
